UNITED STATES PATENT OFFICE.

AUGUST RUETZ AND ROBERT G. DALLMANN, OF MILWAUKEE, WISCONSIN.

TOWEL SUPPORT.

Application filed March 10, 1927. Serial No. 174,238.

In bowling alleys, it is customary to hang towels upon posts or the like, in order that the bowlers may dry their hands whenever desired, by simply grasping the towel and sliding the hand downwardly thereon. To effectively support towels under such usage is very difficult and injury is often inflicted both upon the towel and its supporting means. It is the object of my invention however, to provide a new and improved form of towel support which will tenaciously hold the towel in a manner preventing it from being pulled loose, and in a way which is proof against injury both to the support and the 15 towel.

With the foregoing in view, the invention resides in the novel subject matter herein-after described and claimed, the description being supplemented by the accompanying 20 drawing.

Fig. 1 is a front elevation showing the device in use.

Fig. 2 is a top plan view with the towel in horizontal section.

Fig. 3 is a front elevation of the support independent of the towel.

Fig. 4 is a vertical sectional view on line 4-4 of Fig. 1.

In the drawing above briefly described, the 30 numeral 5 designates a suitably shaped plate preferably formed of metal and adapted to be secured to a post or other support 6, by screws or other desired fasteners 7. Rigidly connected to the plate 5 and preferably 35 formed integrally therewith, is a horizontally disposed loop 8, and spaced from the plane in which said loop is located, is a hook 9 rigidly secured to the plate 5, said plate and hook being preferably united integrally.

To support a towel 10 by means of the device, said towel is folded upon itself as at 11, between its ends, and the folded portion of this towel is passed upwardly through the loop 8, the fold 11 being then hooked over the 45 hook 9. Thus, the towel is tightly held within the loop 8 with its end portions depending from said loop and no matter how hard these end portions are grasped and pulled upon when drying the hands, the towel will remain effectively supported and no injury 50

will result either to the towel or its support.

Excellent results are obtainable from the details disclosed and they are therefore preferably followed. However, within the scope of the invention as claimed, variations may 55 of course be made.

We claim:—

1. Means for supporting a towel which has been gathered together laterally and folded upon itself between its ends, comprising an attaching member, a stationary loop projecting outwardly from said member in a horizontal plane and through which the folded portion of the towel may be passed, said loop being of a size to be substantially filled by 65 the folded portion of the towel within it, and a hook on the member to enter the fold of the towel, said hook being arranged in closely spaced relation to the loop and projecting outwardly from the member and across the 70 loop, whereby the towel will be gripped by its engagement with the hook and loop and prevented from slipping thereon when its projecting free portions are in use.

2. Means for supporting a towel which has 75 been gathered together laterally and folded upon itself between its ends, comprising an attaching plate, a stationary horizontally disposed loop projecting outwardly from said plate at substantially right angles thereto, through which the folded portion of the towel may be passed, and a hook projecting from said plate in spaced relation to the loop and above the same to receive the fold of the towel, said hook projecting upwardly and across the center of the loop, the size of the loop being such that the folded portion of the towel will closely fit it whereby the towel will be prevented from being pulled from the hook when in use.

3. Means for supporting a towel which has been gathered together laterally and folded upon itself between its ends, comprising a one piece device including a substantially triangular attaching plate formed along its base with an outwardly and horizontally extending stationary loop through which the folded portion of the towel may be passed, said loop being of a size to be substantially filled by 95 the folded portion of the towel within it, said 100

plate being also formed on its upper central portion with an upwardly and outwardly inclined stationary hook projecting over the center of the loop and spaced slightly above the same, said hook receiving the fold of the towel after it has been passed through the loop, the relative proportions of the hook and

loop being such that the towel will be prevented from being pulled from the hook and loop when in use.

In testimony whereof we have hereunto affixed our signatures.

AUGUST RUETZ.
ROBERT G. DALLMANN.
